ROBERT FITTS, JR., OF FITCHBURG, MASSACHUSETTS, ASSIGNOR TO THE W. HEYWOOD CHAIR COMPANY, OF THE SAME PLACE.

Letters Patent No. 87,768, dated March 16, 1869.

IMPROVEMENT IN THE CONSTRUCTION OF CHAIRS.

The Schedule referred to in these Letters Patent and making part of the same.

To all whom it may concern:

Be it known that I, ROBERT FITTS, Jr., of Fitchburg, Worcester county, Massachusetts, have invented a new and useful Improvement in Chairs; and I do hereby declare that the following is a full, clear, and exact description thereof, which will enable others skilled in the art to make and use the same, reference being had to the accompanying drawings, forming part of this specification, in which—

Figure 1 is a front view of my improved chair.

Figures 2 and 3 illustrate modifications of the same. Similar letters of reference indicate corresponding parts.

My invention has for its object to improve the construction of chairs, and consists in securing the bow-parts or braces of the chairs to the other parts of the frames, by means of metallic screw-sockets, as hereinafter more fully described.

A are the legs,

B is the bottom, and

C is the back of the chair.

The front legs, A, are connected to each other, and are held in their proper relative positions by a bow, D, the middle part of which is attached to the under side of the forward part of the chair-bottom B, by screws or other substantial means.

The ends of the bow D are inserted in metallic sockets E, the shanks of which are cast with screw-threads, so that they may be screwed into the legs A.

The cavity of the sockets E is made wider in its

lower part than at its mouth, and the ends of the bows are secured in place in the sockets E by wedges, inserted in the ends of said bow, which, as the said ends are forced into the said sockets, are driven into their places, securely fastening the ends of the bows into said sockets.

By this construction, it will be impossible for those who are accustomed to lean back, with their chairs standing upon their hind legs, to find a resting-place for their feet upon the front rounds of the chair.

The metallic sockets E may also be used for attaching bent or curved arms to the bottom, B, and to the pillars of the back C, as shown in red, in fig. 2, or for attaching a curved or bent back to the bottom, B, as shown in red in fig. 3.

In fact, the metallic sockets E may be used for securing the ends of any of the bow-parts of the chair-frame to their places, whether said bows be made of bent or sawn stuff.

I claim as new, and desire to secure by Letters Patent—

The combination of the metallic screw-sockets E, and bow D, with the bottom and legs, or the bottom and back of a chair, substantially as herein shown and described, and for the purpose set forth.

ROBERT FITTS, JR.
